BENJAMIN A. GRAMM, OF LIMA, OHIO.

WAGON-BODY-ELEVATING MECHANISM.

1,195,671.

Specification of Letters Patent. Patented Aug. 22, 1916.

Application filed February 28, 1916. Serial No. 81,046.

To all whom it may concern:

Be it known that I, BENJAMIN A. GRAMM, a citizen of the United States of America, residing at Lima, in the county of Allen and State of Ohio, have invented certain new and useful Improvements in Wagon-Body-Elevating Mechanisms, of which the following is a specification, reference being had to the accompanying drawings.

This invention relates to improvements in wagon-body elevating mechanisms and particularly to improvements in mechanisms for elevating the body of vehicles designed for the transportation of material, such as coal, broken stone and the like, that is adapted to be discharged from the vehicles through a chute; and an object of this invention is to provide an elevating mechanism of the kind hereinbefore referred to which will be balanced in operation irrespective of the distribution of the load raised thereby.

Another object of this invention is to provide a wagon-body elevating mechanism which will be simple in construction, comparatively cheap in manufacture, and efficient and durable in operation and use.

In the drawings illustrating the principle of this invention and the best mode now known to me of applying that principle, Figure 1 is an elevation of a motor-truck having a wagon-body equipped with my new elevating mechanism; Fig. 2 is a plan of the wagon-body; Fig. 3 is a detail showing the rack-and-pinion construction provided at the corners of the wagon-body; Fig. 4 is a plan of the mechanism shown in Fig. 3; and Fig. 5 is a detail illustrating in vertical section the upper end of the hoisting cylinder.

The motor-truck *a* comprises the chassis or frame *b*, the wheel *c* upon which the latter is supported, the motor *d*, the steering-wheel *e* and the driver's seat *f*, all shown somewhat diagrammatically in Fig. 1. Mounted upon the chassis *b* is a stationary four-sided vertical frame *g* having two ends *h* and two sides *i*; and, within this frame *g*, there is placed a four-sided wagon-body *j* that is free to be moved up and down within the frame *g*. At each end of each side *j'* of the wagon-body *j*, there is fastened a vertically-disposed elongated plate *k* one side of the outer or front face of which is toothed to form a vertical rack *k'*, the remaining side *k''* of this face of the plate *k*

being left plane (Figs. 1 and 3). Similarly, there is fastened, at each side of each end *j'* of the wagon-body *j*, a vertically-disposed plate substantially the same as the plate *k* fastened to the sides *j'*. At the top of each of the four corners of the stationary frame *g*, there is mounted a shaft-bearing *m* in which are rotatably mounted an end of a side-shaft *n* and an end of an end-shaft *o*; the two side-shafts *n* and the two end-shafts *o* are, of course, horizontally disposed. On each end of each of the shafts *n*, *o*, there is keyed a pinion *p* that meshes with the teeth *k''* of the rack *k'* opposed thereto; and, adjacent to each of the pinions *p*, there is loosely mounted on the same shafts *n*, *o*, an idler *q* that rolls on the plane surface *k''*. These idle rollers *q* maintain the pinions *p* in proper position relative to the rack-teeth *k''* and prevent side sway of the wagon-body *j* during the raising of the same. The wagon-body *j* illustrated in the drawings is divided into two compartments *r* but it is obvious that there may be provided at will any reasonable number of such compartments. As shown in Fig. 2, there is provided, in the bottom of each of these compartments *r*, a slide-controlled opening *r''* through which the contents of the compartment is discharged into a suitably-placed chute (not shown), when the wagon-body *j* has been raised to the proper height.

To elevate the wagon-body *j*, the following hydraulic hoisting mechanism is provided (Figs. 1, 2 and 3): Between the compartments *r*, there is built into the wagon-body *j* at the center thereof a vertically-disposed tube or cylinder *s* the upper end of which is closed by a cap or cylinder-head *t*; and, within this cylinder *s*, there works slidably a piston or ram *u*, which is raised by the pressure of a suitable liquid (such as oil) forced into the cylinder *s* beneath the ram *u* by means (for example) of a rotary pump shown conventionally at *v*. This force pump *v* may be driven by the propeller-shaft *w* of the auxiliary driving mechanism shown and described in my application Serial No. 77,831, filed February 12, 1916. The upward pressure of the ram *u* against the leveling washer *t'* (Fig. 5) within the cylinder *s* is transmitted to the cylinder-head or cap *t* of the latter and serves to move the wagon-body *j* upwardly.

The operation of the elevating mechanism

just described is balanced, rapid and smooth. Even if one of the compartments *r* be empty and the other completely full, the filled end of the wagon-body *j* will move upwardly at 5 the same instant as the empty end; for, just as soon as the pinions *p* at the empty end begin to rotate, the side-shafts *n* commence to turn and cause the pinions *p* at the full end simultaneously to revolve. It follows 10 that one end of the wagon-body *j*, whether that end be full or empty, will begin to move upwardly at just the same time as the other end thereof; and this result is due to the stabilizing action of the shafts and the rack- 15 and-pinion mechanism and to the central position of the hydraulic raising mechanism hereinbefore described.

While I have hereinbefore described the ram *u* as being raised by fluid force there- 20 under by a rotary pump *v*, yet it is obvious to all skilled in this art that other means may be used for driving the ram *u* up- 25 wardly. Again, while this invention has been herein described and shown in connection with a self-propelled vehicle, yet this invention may equally well be applied to a horse-drawn vehicle.

I claim:

1. A wagon-body elevating mechanism in- 30 cluding a wagon-body member; a frame member within which said wagon-body member is movably arranged; means for raising said wagon-body member; and mech- 35 anism independent of said means for insur- ing that both ends of the latter move up- 40 wardly substantially simultaneously, said mechanism being arranged to transmit the movement of one end of said wagon-body member to the other end thereof and cause both ends to move at substantially the same time.

2. A wagon-body elevating mechanism in- 45 cluding a wagon-body member; a frame member within which said wagon-body member is movably arranged; centrally- 50 disposed means for raising said wagon-body member; and mechanism independent of said means for insuring that both ends of the latter move upwardly substantially si- 55 multaneously, said mechanism being ar- ranged to transmit the movement of one end of said wagon-body member to the other

end thereof and cause both ends to move at substantially the same time.

3. A wagon-body elevating mechanism in- 55 cluding a wagon-body member; a frame member within which said wagon-body member is movably arranged; means for raising said wagon-body member; mech- 60 anism independent of said means for insur- ing that both ends of the latter move up- 65 wardly substantially simultaneously, said mechanism being arranged to transmit the movement of one end of said wagon-body member to the other end thereof and cause both ends to move at substantially the same time; and means for preventing swaying of the wagon-body member during the up-and- 70 down movement of the same.

4. A wagon-body elevating mechanism in- 70 cluding a wagon-body member; a frame member within which said wagon-body member is movably arranged; a pair of 75 racks on each side of one of said members, the racks on the same side being arranged at opposite ends of the member; a pair of shafts arranged on opposite sides of the other of said members and extending length- 80 wise thereof; pinions on said shafts and in mesh with said racks; and mechanism inde- 85 pendent of said shafts and pinions for rais- ing said wagon-body member.

5. A wagon-body elevating mechanism in- 85 cluding a wagon-body member; a frame member within which said wagon-body member is movably arranged; a pair of 90 racks on each side of one of said members, the racks on the same side being arranged at opposite ends of the member; a pair of shafts arranged on opposite sides of the other of said members and extending length- 95 wise thereof; pinions mounted on said shafts and in mesh with said racks; and rollers mounted on said shafts and ar- ranged to bear against the rack-carrying member for the purposes set forth.

In testimony whereof I have hereunto set my hand at Lima, Ohio, this twenty-first day of February, A. D. 1916, in the presence of the two undersigned witnesses.

BENJAMIN A. GRAMM.
